YIELDABLE PIPE WRENCH

Floyd L. Scott and Ralph P. Sherman, Houston,
Tex., assignors to Hughes Tool Company, Houston, Tex., a corporation of Texas

Application July 16, 1936, Serial No. 90,840

4 Claims. (CL 81—53)

Our invention relates to pipe wrenches and particularly wrenches for screwing pipe joints such as are employed on drill stems or casing employed in deep well drilling by the rotary method.

5 It is an object of the invention to provide a pipe wrench the handle of which will yield under a predetermined pressure so as to indicate that the desired amount of torque has been reached in the joint screwing operation.

10 It is particularly adapted for use on tool joints where the threads must be made up tightly to assure a seal, but where excessive pressure on the threads in screwing up will injure the threads and the shoulders of the joint.

15 We desire to provide an indicator which will indicate when the joint is sufficiently tight by moving a recorder and sounding an alarm note.

The device is intended as an attachment to any desired type of pipe wrench.

20 In the drawing herewith Fig. 1 is a top plan view of a wrench employing the invention, the attachment being in longitudinal section.

Fig. 2 is a transverse section taken on the plane 2—2 of Fig. 1.

25 Fig. 3 is a similar transverse section on the plane 3—3 of Fig. 1.

Our invention is shown as employed with a pipe wrench of ordinary construction. It has a handle 5 to the forward end of which are pivoted 30 two sectional jaws 6 and 7 which together are adapted to enclose a pipe joint. A latch 8 serves to latch said jaws together.

The handle 5 has an eye 9 at its outer end through which a pin 10 is received. Said outer 35 end of the handle fits within a bifurcated recess 11 in an arm 12. The pin 10 extends across said recess and forms a pivotal connection of the handle 5 with the arm 12.

Said arm has its outer end formed with an opening 13 and a clevis 14 by means of which it may be anchored against movement when in use. Said arm extends forwardly along the wrench handle and is spaced somewhat therefrom, its forward end being connected to said handle by means of 45 a yoke such as is shown in Fig. 2.

Said yoke comprises a frame 15 having a central recess 16 to receive the wrench handle 5. The open side of this recess is closed about the wrench handle by a plate 17 secured to the yoke 50 by set screws or other means. At each side of the recess is a chamber in which is housed a spring 18. A set screw 19 extends through the closed wall of the chamber and bears against a block 20 upon which the spring 18 is seated. 55 The other end of the chamber is closed by a cap

21 through which a post 22 projects. Said post has a radial flange 23 thereon, within the chamber, which acts as a seat for the spring 18 which holds the post resiliently outwardly. The flange also limits the outward movement of the post 5 under pressure of the spring.

The two posts 22 project from the yoke or housing and bear against the forward end of the arm 12, thus holding said arm resiliently away from the wrench handle.

10 We also provide a band of metal 24 shown best in Fig. 3 which encloses the handle 5 closely and has a loop 25 extending about the arm 12 and spaced therefrom as will be seen in the drawing. This band also acts to limit the movement of the 15 arm relative to the handle.

The extreme forward end of arm 12 has a short finger 26 thereon which normally engages over the projecting end of a strip of spring steel 27 which acts as an alarm. When vibrated by the 20 arm it gives off a note which informs the operator that the arm has moved relative to the wrench handle. The steel strip is anchored to the handle by attachment to a sleeve 28 fixed to the handle by a set screw 29.

25 A counter or recorder may also be mounted on the handle to indicate the number of joints screwed up. A counter of old construction is shown at 30. A finger 31 projects toward the handle from the arm 12. A spring 32 holds this 30 finger normally in position against the handle 12. When the arm yields in use it will swing the finger 31 sufficiently to move a recording wheel in the counter and make a record thereof. Such recorders can be purchased in the market and 35 form no novel portion of our invention.

In the use of this device, it may perform various duties. Considering the process of screwing up tool joints, the lower section of pipe extending into the well will be held stationary in the rotary 40 and the upper stand of pipe with a tool joint pin at the lower end will be raised over the stationary section of the joint and the pin member at the lower end of the new stand will be stabbed into the box of the section in the well. The cat line 45 is then ordinarily looped about the new section to rotate it and screw the pin into the box. When thus screwed up the joint is not tight enough. The wrench will then be engaged about the upper section of the joint and a jerk line will be secured to the eye 13 of the wrench arm and a further 50 pull will be exerted thereon in the direction of the arrow. A predetermined amount of torque will be exerted before the springs 18 will be compressed sufficiently to force the arm 12 toward the 55

handle so as to snap it past the alarm member 27 and cause it to vibrate and indicate that the joint is tight enough. The movement of the arm 12 relative to the wrench handle to ring the alarm 5 will also actuate the counter 30.

With this safety wrench it is assured that excessive torque will not be exerted upon the joint to gall the threads or the shoulders of the joint. The counter will show how many joints have been 10 thus tightened and serves as a check by the superintendent as to whether or not all the joints have been thus carefully tightened by means of the wrench or whether such tightening has been omitted on some of them.

15 While we have illustrated the invention as applied to one operation it is obvious that it may be used for other purposes and the wrench handle may be held stationary while the pipe is rotated.

What we claim as new is:

20 1. A pipe wrench including a handle, pipe engaging members thereon, an arm pivotally attached to the outer end of said handle at one of its ends and extending along said handle approximately parallel therewith and spaced therefrom, said arm also projecting slightly beyond the outer end of said handle and adapted for attachment 25 to a pull line, means to resiliently oppose the movement of the inner end of said arm toward said handle and means to indicate when a predetermined pull is exerted upon the outer end of said arm.

25 2. A pipe wrench including a handle, pipe engaging members thereon, an arm pivotally attached to the outer end of said handle at one of

its ends and extending along said handle approximately parallel therewith and spaced therefrom, said arm also projecting slightly beyond the outer end of said handle and adapted for attachment 5 to a pull line, means to resiliently oppose the movement of the inner end of said arm toward said handle and an alarm device, actuated by the movement of said arm toward said handle a predetermined amount.

3. A pipe wrench, a handle, pipe engaging 10 means on the inner end thereof, an arm parallel therewith, means to secure said arm between its ends pivotally to the outer end of said handle, said arm projecting inwardly adjacent said handle, yieldable means to hold the inner end of said arm spaced from said handle, said yieldable means being adapted to permit relative movement 15 of said arm in response to a predetermined pull exerted upon the outer end of said arm.

4. A pipe wrench, a handle, pipe engaging 20 means on the inner end thereof, an arm parallel therewith, means to secure said arm between its ends pivotally to the outer end of said handle, said arm projecting inwardly adjacent said handle, yieldable means to hold the inner end of 25 said arm spaced from said handle, said yieldable means being adapted to permit relative movement of said arm in response to a predetermined pull exerted upon the outer end of said arm and an indicator actuated by the relative movement of said 30 arm toward said handle.

FLOYD L. SCOTT.
RALPH P. SHERMAN.
